FISHING PLUG

Edward W. Smith, Naval Base, S. C.

Application January 23, 1953, Serial No. 23,269

Term of patent 14 years

(Cl. D31—4)

To all whom it may concern:

Be it known that I, Edward W. Smith, a citizen of the United States of America, residing at Naval Base, State of South Carolina, have invented a new, original, and ornamental Design for a Fishing Plug, of which the following is a specification, reference being had to the accompanying drawings, forming part thereof.

In the drawing:

Fig. 1 is a side elevational view of a fishing plug, showing my new design;

Fig. 2 is a front elevational view of the plug;

Fig. 3 is a top plan view of the plug;

Fig. 4 is a rear elevational view of the plug;

Fig. 5 is a bottom plan view of the plug; and

Fig. 6 is a sectional view taken substantially along the line 6—6 of Fig. 1.

The dominant features of my design are shown in full lines.

I claim:

The ornamental design for a fishing plug, substantially as shown and described.

EDWARD W. SMITH.
